UNITED STATES PATENT OFFICE.

LOREN W. PENNEY, OF NEWTON, MASSACHUSETTS, ASSIGNOR TO SACO-LOWELL SHOPS,
OF BOSTON, MASSACHUSETTS, A CORPORATION OF MASSACHUSETTS.

SAFETY DEVICE FOR LAP-WINDERS AND THE LIKE.

1,122,631.

Specification of Letters Patent.

Patented Dec. 29, 1914.

Application filed August 10, 1914. Serial No. 856,070.

To all whom it may concern:

Be it known that I, LOREN W. PENNEY, of Newton, in the county of Middlesex and State of Massachusetts, a citizen of the 5 United States, have invented a new and useful Improvement in Safety Devices for Lap-Winders and the like, of which the following is a specification.

In lap winders as ordinarily constructed 10 there are two fluted rolls on which the core about which the lap is wound is supported and on the core rests a top roll of similar character and of great weight operated by power. In practice the operator winds the 15 lap around the core and sets the core in position after which the top roll is lowered. If he sees that the lap is not winding properly upon the core the temptation is to straighten or even it out by hand and unless 20 he is careful his hand will be drawn in between the core or lap and top roll and severely jammed. My invention is intended to prevent such an accident by providing a shield which when the machine is started 25 is positively locked in place, lying between the operator and the top roll and core so that it cannot be removed to expose the core without lifting the top roll again. Thus after the top roll has been lowered and the 30 operation of winding has begun the operator cannot by any possibility get behind the shield to straighten out the lap except by lifting the top roll to its highest position which automatically unlocks the shield, or 35 at least lifting the top roll sufficiently high above the core to allow his hand to have perfect freedom of action about the core without any danger of accident.

My invention will be understood by reference 40 to the drawings wherein it is shown in its preferred embodiment, and in which—

Figure 1 is a front view of a lap winder to which the improved shield has been applied, Fig. 2 being a side view thereof with 45 the shield in position to prevent access to the core and lap, and Fig. 3 being a similar side view, the shield being in its withdrawn position.

I have shown my invention applied to a 50 lap winder of the kind described in Letters Patent No. 1,029,391, dated June 11, 1912, issued on an application filed by Charles Mills and myself. It will readily be seen, however, that my invention may be applied 55 to other lap winders.

A is the frame within which slide vertically in the usual manner the slides B, B¹ mounted in ways a, the top roll being lettered C; C¹, C² being the usual bottom rolls, this mechanism being all of it operated in 60 any usual and convenient manner.

The core upon which the lap is wound and which is indicated at D rests upon the rolls C¹, C² and on it rests the top roll C, which is journaled in the slides B, B¹. As the lap 65 grows as it is wound upon the core the top roll C is lifted from the position shown in dotted lines in Figs. 2 and 3 to the position shown in full lines in Fig. 3 and as it is lifted by the increasing size of the lap it 70 lifts with it the slides B, B¹. Trunnions e, e¹ are mounted to turn in the upper ends of the slides B, B¹ and to those trunnions is rigidly attached the shield so that it may be lifted at the proper time about the 75 trunnions as an axis. The shield comprises two parts, the part E which is attached to the trunnions and the part E¹ which is hinged at e² thereto. I prefer to locate the 80 hinges e² back from the free edge of the part E as shown so that while the part E¹ may drop into vertical position when the part E is lifted as shown in Fig. 3, it cannot be pulled forward to get access to the mechanism behind it when the part E is in 85 its lower position. I also prefer to provide the part E¹ with slots E² so that the winding operation may be watched. As shown in Fig. 1 the portion E of the shield is somewhat narrower than the portion E¹. 90 This allows the portion E to hang between the two side frames A of the machine while the lower or hinged part E¹ of the shield will slide upon the flanges a¹ which form the inner edges of the frame, these flanges 95 holding the portion E¹ away from the moving parts of the machine.

The trunnion e carries a rocker F having preferably pins f, f¹ projecting laterally from it, and to this rocker the part E of the shield is bolted, it forming the means of rigid attachment between the shield and this trunnion so that this rocker and the shield form a lever of which the trunnion e is the fulcrum and the pins f, f¹ project from the 103 rocker one on each side of the fulcrum. The pin f¹ forms a stop which on engagement with the upper portion of the slide B will serve as a stop to prevent the part E of the shield when in lowered position from falling in 110

against the top roll. The pin *f* forms one member of a lock to prevent the shield from being lifted except at a time when it may be with safety. The other member of the lock is the arm *G* which is mounted on the upper part of the frame *A* near enough to the pin *f* to engage it and hold the rocker *F* positively in an upwardly-projecting position (see Fig. 2) and then lock it and the shield from being lifted. The upper end of the arm *G* is preferably hook-shaped so that a recess *g* capable of receiving the pin *f* is formed and the extremity *g*¹ of the hook projects preferably beyond the face of the arm *G* so as to insure the restraint of the further upward movement of the pin *f* and its end of the rocker *F* as the slide *B* continues to rise on the further enlargement of the lap roll and the consequent lifting of the top roll (see Fig. 3).

The operation of this mechanism is simple. As the top roll is lowered from its position shown in Fig. 3 to the position shown in Figs. 1 and 2 the pin *f* is pulled out of the recess *g* and rides down the face of the arm *G* into the position shown in Fig. 2. It will be seen that the distance between the trunnion *e* and the arm *G* is less than the distance of the pin *f* from the arm *G* so that the shield cannot possibly be lifted when the top roll is in its lower position or until it has been lifted sufficiently high to allow the pin *f* to project into the recess *g* when the shield will automatically be lifted.

I am aware that shields have heretofore been applied to machines of this general character, but so far as I know it has always been possible to lift such shield out of the way at any time during the lap winding operation so that the operator could by one means or another get behind the shield at any time, the shield serving merely as a suggestion to him that he had better not risk an accident, but so far as I know no shield has been constructed heretofore by which the operator is absolutely prevented from tampering with the core or lap after the machine has once been started except by rendering the top roll ineffective and so removing all danger. Believing therefore that I am the first to lock a shield permanently during the dangerous period of the machine's operation, so that access cannot be had to the rolls or lap, I do not wish to limit myself to the precise construction shown nor to the use of such a device on lap winders only. The lock may be modified in construction and be within the scope of my claims whether it is attached to a lap winder or other like machine.

While I prefer to provide the upper end of the arm *G* with a hook-shaped finger, this is not necessary. The hook may be omitted, the arm thus serving as a lock as before so long as the pin *f* is in engage-

ment therewith and releasing the pin as the slide carries it above the arm.

In some cases it may be desirable to duplicate the lock on the other side of the machine.

What I claim as my invention is:—

1. In a machine of the kind described, slides, a shield, positive means for locking said shield whereby it cannot be lifted when said slides are at one extremity of their movement, and means for lifting said shield automatically when said slides are approximately at the other extremity of their movement. 75

2. In a machine of the kind described, a frame, slides mounted to slide with relation thereto, a pivoted shield mounted to move with said slides, a rocker attached to said shield and projecting rearwardly therefrom, an upright arm fixedly mounted on said frame in close relation to said rocker whereby the rearwardly-projecting end of said rocker will be prevented from being depressed to lift the shield while said rocker and said arm are in contact. 80

3. In a machine of the kind described, a frame, slides mounted to slide with relation thereto, a pivoted shield mounted to move with said slides, a rocker attached to said shield and projecting rearwardly therefrom, an upright arm fixedly mounted on said frame in close relation to said rocker whereby the rearwardly-projecting end of said rocker will be prevented from being depressed to lift the shield while said rocker and said arm are in contact, said arm being provided with a recess at its upper end adapted to allow the rocking of said rocker. 90

4. In a machine of the kind described, a frame, slides mounted to slide with relation thereto, a pivoted shield mounted to move with said slides, a rocker attached to said shield and projecting rearwardly therefrom, an upright arm fixedly mounted on said frame in close relation to said rocker whereby the rearwardly-projecting end of said rocker will be prevented from being depressed to lift the shield while said rocker and said arm are in contact, said arm being provided with a hook-shaped finger at its upper end, said finger forming a recess to allow the rocking of said rocker, said finger being adapted to restrain the upward movement of the engaging extremity of said rocker whereby as the slides continue to rise 105 said extremity of said rocker will be prevented from rising and said shield will be lifted. 110

5. In a machine of the kind described, a frame, slides mounted to slide with relation thereto, a shield comprising two members one pivotally mounted on said slides and the other hinged to the lower edge of said first member, and means for locking said shield when the slides are at one extremity 125 130

of their movement and for releasing it at the other extremity of their movement, the hinges connecting said shield members being located on the under side of said pivot-
5 ed member and slightly back from its lower edge, whereby said lower edge will form a stop to prevent said hinged member from being pulled forward, but will allow it to swing freely rearwardly when occasion per-
10 mits.

6. In a machine of the kind described, a frame comprising two slide members, two bottom rolls, a top roll, slides in said frame to support said top roll, a shield adapted
15 when said top roll is in its lowest position to hang in front thereof and prevent access

thereto, and means for positively locking said shield in said position until said top roll is approximately in its highest position, said shield comprising an upper member 20 and a lower member hinged together whereby said lower member cannot be pulled forward of said upper member, said upper member being narrower than the distance between the side members of said frame and 25 the lower member being sufficiently wide to ride on said side members of said frame.
